UNITED STATES PATENT OFFICE.

THOMAS B. ROSS, OF EVANSVILLE, INDIANA, ASSIGNOR TO THE ROSS SASH LOCK COMPANY, OF SAME PLACE.

SASH-BALANCE.

SPECIFICATION forming part of Letters Patent No. 426,070, dated April 22, 1890.

Application filed February 8, 1889. Serial No. 299,223. (No model.)

To all whom it may concern:

Be it known that I, THOMAS B. ROSS, a citizen of the United States, residing at Evansville, in the county of Vanderburg and State 5 of Indiana, have invented certain new and useful Improvements in Sash-Locks or Window-Fasteners; and I do declare the following to be a full, clear, and exact description of the invention, such as will enable others 10 skilled in the art to which it appertains to make and use the same, reference being had to the accompanying drawings, and to the letters of reference marked thereon, which form a part of this specification.

15 This invention relates to improvements in window-fasteners, and has for its object to lock the sash in any position in which it may be placed, and thus prevent the sash from being either raised or lowered; and it consists, 20 essentially, in combining a locking pawl or key with a gear-wheel located in a box and adapted to revolve upon a stud forming a part of one of the outer sides of the box, the said stud being so arranged as to constitute 25 the rivet or means of fastening the opposite sides of the box to each other, thereby simplifying the construction and cheapening the manufacture; also, in locating the box in the window-casing in such position that the gear- 30 wheel is adapted to engage a rack-bar attached to the adjacent edge of the window-sash.

Figure 1 is a side elevation of a part of a sash and window-frame, in section, and the 35 box with one of the sides removed. Fig. 2 is a detached view of the box complete and portion of the window-frame indicated in dotted lines. Fig. 3 is a detached view of the shield having a central opening adapted to receive 40 and hold the key by means of which the pawl may be raised, so as to permit the gear-wheel to revolve. Fig. 4 is a view of the top of the box, showing the pawl in dotted lines, also the key inserted therein and the shield in 45 section. Fig. 5 is a detached view of the key. Fig. 6 is a detached plan view of the pawl. Fig. 7 is a side view of the pawl. Figs. 8 and 9 show a modified form of the fastener in which the key is forced endwise in between 50 the teeth of the gear-wheel to lock it by the action of the spiral spring. Figs. 10, 11, and

12 represent another modified form of the device, in which a lever takes the place of the keys indicated in the previous figures, the said lever being adapted to raise the pawl 55 and disengage it from the gear-wheel, and thus permit it to revolve upon its stud.

The letter A indicates the window-frame; B, the sash; C, the rack-bar, which may be either a casting or of corrugated sheet metal. 60

C' is the gear-wheel.

D is one side of the box, and D' is the other, having a stud d, which is an integral part of that side of the box.

d' is a small recess in the upper part of the 65 box to receive and maintain in proper position a small spiral spring E, the lower end of which engages with a small stud f, forming a part of the pawl F. The spring E serves the purpose to make the action of the pawl F 70 quicker than it might be if dependent solely upon its specific gravity to lock the gear-wheel. The pawl F has a boss f' on each side, which enters a depression in the opposite sides of the box, (indicated in dotted lines in 75 Fig. 4.) The bosses f' serve the purpose of trunnions and enable the pawl to oscillate thereon, and thereby enable it to drop into the spaces between the teeth of the gear-wheels. 80

f'' is a square opening penetrating the pawl F, of the same cross-section as the key G, which is adapted to fit closely therein, and by means of which the pawl may be turned on its axis and its point F' be raised from between the teeth of the gear-wheel and permit the latter to revolve. The key G is pointed at g to facilitate its entrance into the opening f''. It has a round cross-section at g' to permit it to turn readily in the shield 90 H. It has also a lip g'', which prevents it from becoming accidentally detached from the shield H through the opening H' and notch h, the notch h permitting the lip g'' to pass through when the key is inserted in 95 the opening H'. The key G is also provided with a handle g''', by means of which it may be turned upon its axis. When the key has been inserted through the opening H' and notch h and has entered the opening f'', it 100 can only be removed therefrom by turning the key until the lip g'' is on a line with the

notch *h*. When in this position, the key may be withdrawn, and the fastener will then remain locked.

This sash-fastener is to be used either on cars or house-windows, and is an improvement upon the one for which Letters Patent were granted me, No. 319,324, June 2, 1885.

Having described my invention, what I desire to secure by Letters Patent, and claim,

is—

The combination, with the pawl *F*, located in the box *D D'*, and the shield *H*, having an opening *H'* and a notch *h*, of the detachable key pointed at one end and provided with a

lip *g''* near the other, the said key being 15 rectangular in cross-section for a portion of its length to fit the rectangular opening in the pawl and round in cross-section adjacent to the lip *g''* to permit it to turn readily in the shield, substantially as and for the purposes set forth.

In testimony whereof I affix my signature in presence of two witnesses.

THOMAS B. ROSS.
